The ornamental design for a bottle cap bead, as shown and described.

DESCRIPTION

FIG. 1 is a perspective view of one side and the front of the bottle cap bead showing my new design;

FIG. 2 is a front view thereof, the back view being a mirror image;

FIG. 3 is a top view thereof, the bottom view being a mirror image; and,

FIG. 4 is a left side view thereof, the right side view being a mirror image.

The broken lines shown in the drawings represent portions of the bottle cap bead that form no part of the claimed design.
